10 Claims. (Cl. 260—438)

This invention relates to improvements in the manufacture of dialkyl alkanephosphonates.

There are already available methods described in the chemical literature for the preparation of dialkyl alkanephosphonates of which the two principal methods are as follows. First, a trialkyl phosphite is reacted with an alkyl halide, preferably the bromide or iodide, in accordance with the well-known Arbusov reaction which proceeds in accordance with the following equation—

In this equation R and R' indicate alkyl groups and X indicates a halogen atom. In this process where R and R' are the same it is only necessary to use very small quantities of the alkyl halide since, as will be seen from the above Equation 1 the alkyl halide is regenerated.

This method of preparing the dialkyl alkanephosphonates, however, suffers from marked disadvantages because, on the one hand, the trialkyl phosphites are compounds which are difficultly accessible on a commercial scale and their preparation involves the use of large quantities of organic tertiary bases such as pyridine or diethyl aniline; furthermore, where R and R' represent different alkyl groups the reaction product will be a mixture of differing alkanephosphonates depending upon the relative reactivities of the two halides RX and R'X.

An alternative method which is available involves the reaction of the sodium salt of a dialkyl phosphite with an alkyl halide, preferably the bromide or iodide, in accordance with the following equation—

This method is greatly superior to that in Equation No. 1 where dialkyl alkanephosphonates are to be prepared in which R and R' represent different alkyl groups. This method, however, also has the marked disadvantage that it involves the use of metallic sodium on a large scale in connection with the manufacture of sodium alkoxide or of powdered sodium for the conversion of the dialkyl hydrogen phosphite to the desired dialkyl sodium phosphite and the hazards involved in the use of metallic sodium on a large scale are obvious.

We have now found that we can produce dialkyl alkanephosphonates conveniently by processes which avoid the use of trialkyl phosphites (which are themselves somewhat sensitive to traces of moisture, particularly in the case of trimethyl phosphite) and which also overcome the disadvantage of the use of metallic sodium by the second above-mentioned method.

The present invention is based upon the discovery that a cuprous halide addition compound or complex with a trialkyl phosphite undergoes thermal decomposition, yielding as a reaction product the desired dialkyl alkanephosphonate.

According to the present invention therefore there is

2

provided a process for the manufacture of dialkyl alkanephosphonates which comprises subjecting a cuprous halide addition compound or complex with a trialkyl phosphite to thermal decomposition.

5 The invention also provides a process for the manufacture of dialkyl alkanephosphonates which comprises reacting a cuprous halide with a phosphorus trihalide and with an alkanol in the cold and thereafter subjecting the cuprous halide-alkyl phosphite addition compound or complex thereby produced to thermal decomposition.

The cuprous halide compound which is most convenient is cuprous chloride and the phosphorus trihalide which is most convenient is phosphorus trichloride.

10 The decomposition of the cuprous halide addition compound or complex which may be represented by the formula

can be effected by merely heating the solid material to 20 a temperature of approximately 200° C.; the thermal decomposition in this way, however, produces yields which are somewhat low, which may be in the neighbourhood of 20%.

A feature of the invention therefore consists in that 25 the thermal decomposition of the cuprous halide-alkyl phosphite addition compound or complex is effected by heating the said addition compound or complex in suspension in a medium which is an inert and stable liquid at the temperature of the thermal decomposition.

30 The reaction may, for example, be carried out in a high boiling solvent such as diphenyl or diphenyl ether.

It will be appreciated that the present invention is not 35 confined to the production of dialkyl alkanephosphonates in which all of the alkyl groups are identical but includes the case where the cuprous halide and phosphorus trihalide are reacted together with a mixture of aliphatic alcohols.

In our copending application, S.N. 308,727, we have 40 disclosed the production of other compounds by decomposition of this complex.

The following example will serve to illustrate the manner in which the present invention may be carried into effect.

Example

45 The cuprous chloride addition compound of trimethyl phosphite was prepared by slowly adding phosphorus trichloride (136 gm.) to a mixture of cuprous chloride (100 gm.) and methanol (96 gm.) in toluene (500 ml.) with vigorous stirring at a temperature of approximately 50 -5° C. There was no marked temperature rise. The solution was green at first but slowly deposited a white solid as the phosphorus trichloride was added. After all the phosphorus trichloride had been added the white solid product $(CH_3O)_3P.CuCl$ was filtered off, washed with dry petrol (200 ml.) and dried in a vacuum desiccator. The yield was 90% of the theoretical amount.

A portion of the white solid thus prepared was rapidly suspended in diphenyl ether and the mixture heated with stirring to 200° C. When decomposition was complete 55 the dimethyl methanephosphonate was distilled out from the diphenyl ether under vacuum (12 mm.). The yield was approximately 70% of the theoretical amount.

We claim:

1. A process of preparing a complex of the formula $(RO)_3P.CuX$ wherein R is a lower aliphatic hydrocarbon group and X is selected from the class consisting of chlorine, bromine and iodine which comprises forming a mixture consisting essentially of at least one lower unsubstituted alkanol, a cuprous halide and an inert solvent, and adding phosphorus trichloride to said mixture at a temperature of the order of -5° C. while agitating said mixture.

2. A process of preparing a complex of the formula $(\text{CH}_3\text{O})_3\text{P} \cdot \text{CuCl}$ which comprises forming a mixture consisting essentially of methanol, cuprous chloride and an inert solvent and adding phosphorus trichloride to said mixture at a temperature of the order of -5° C . while agitating said mixture.

3. A process of preparing a lower unsubstituted dialkyl alkanephosphonate which comprises suspending in a high boiling liquid a complex of the formula $(\text{RO})_3\text{P} \cdot \text{CuCl}$, wherein R represents an unsubstituted lower alkyl group, heating said suspension to a temperature of substantially 200° C . at a pressure of the order of, but not below, normal atmospheric pressure, said liquid being one which is inert and stable at said temperature and pressure.

4. A method as defined in claim 3 wherein said liquid is selected from the group consisting of diphenylether and diphenyl.

5. A method of preparing a lower dialkyl alkanephosphonate which comprises reacting a lower unsubstituted alkanol with cuprous chloride and phosphorus trichloride to form the complex $(\text{RO})_3\text{P} \cdot \text{CuCl}$, where R is a lower unsubstituted alkyl group, and then suspending said complex in a high boiling liquid and heating the resulting suspension at a temperature of substantially 200° C . and a pressure of the order of, but not below, normal atmospheric pressure to thereby decompose said complex and produce said lower dialkyl methanephosphonate, said liquid being one which is inert and stable at said temperature and pressure.

6. A method of producing a lower dialkyl alkanephosphonate which comprises forming a mixture consisting essentially of at least one unsubstituted lower alkanol, cuprous chloride and an inert solvent, adding phosphorus trichloride to said mixture at a temperature of the order of -5° C . to thereby form a complex of the formula $(\text{RO})_3\text{P} \cdot \text{CuCl}$, wherein R is a lower unsubstituted alkyl group, removing said complex from said solvent, suspending said complex in a high boiling liquid, and heating the suspension thus formed at a temperature of substantially 200° C . at a pressure of the order of, but not below, ordinary atmospheric pressure, said liquid being one which is inert and stable at said temperature and pressure.

7. A process as defined in claim 6 wherein said high boiling liquid is selected from the group consisting of diphenyl and diphenylether.

8. A process of producing dimethyl methanephosphonate which comprises forming a mixture of methanol, cuprous chloride, and an inert solvent, adding phosphorus trichloride to said mixture at a temperature of the order of -5° C . while stirring said mixture, thereby forming a complex of the formula $(\text{CH}_3\text{O})_3\text{P} \cdot \text{CuCl}$, suspending said complex in a high-boiling liquid and decomposing said complex by heating the suspension thus formed at a temperature of substantially 200° C . and a pressure of the order of, but not less than, ordinary atmospheric pressure, said high boiling liquid being one which is inert and stable at said temperature and pressure.

9. A process as defined in claim 8 wherein said high boiling liquid is selected from the group consisting of diphenyl diphenylether.

10. A process of preparing dimethyl methanephosphonate which comprises slowly adding phosphorus trichloride to a mixture of cuprous chloride and methanol in toluene with stirring at a temperature of substantially -5° C ., thereby forming the complex $(\text{CH}_3\text{O})_3\text{P} \cdot \text{CuCl}$, removing said complex from said toluene, suspending said complex in diphenylether, decomposing said complex by heating the suspension thus formed substantially to 200° C . with stirring, at atmospheric pressure thereby forming dimethyl methanephosphonate.
